DISPLAY CASE DIVIDER

Tanner S. Chrisler, 5044 Westminster,
St. Louis, Mo. 63108

Filed Oct. 12, 1971, Ser. No. 188,646

Term of patent 7 years

Int. Cl. D6—06

U.S. Cl. D6—85

FIG.1

FIG.2

FIG.3

FIG.4

FIG.5

FIG. 1 is a top plan view of a display case divider embodying my new design;

FIG. 2 is a front elevation thereof;

FIG. 3 is a bottom plan view thereof;

FIG. 4 is a rear elevation thereof; and

FIG. 5 is a left side elevation thereof, the right side being a mirror image of the side shown.

I claim:

The ornamental design for a display case divider, substantially as shown and described.
